[57] CLAIM

The ornamental design for a sports glove, as shown and described.

DESCRIPTION

FIG. 1 is a perspective view of a sports glove showing my new design;

FIG. 2 is a top view thereof;

FIG. 3 is a bottom view thereof;

FIG. 4 is a front plan view thereof; and,

FIG. 5 is a top plan view thereof.

The cross hatch surface shading in all views is understood to repeat throughout the indicated area.

The hand shown in broken line illustrates the environment thereof and forms no part of the claimed design.
